UNITED STATES PATENT OFFICE.

NAOMI FORCE, OF NEW YORK, N. Y.

HAT-FRAME DRIER.

1,160,158.

Specification of Letters Patent. Patented Nov. 16, 1915.

Application filed January 11, 1915. Serial No. 1,653.

To all whom it may concern:

Be it known that I, NAOMI FORCE, a citizen of the United States, and resident of New York, in the county of New York and State 5 of New York, have invented certain new and useful Improvements in Hat-Frame Driers, of which the following is a specification.

This invention relates broadly to dehydrating apparatus. The present main contemplation thereof is to provide a simple and inexpensive embodiment adapted primarily for advantageous utilization in connection with the expeditious, efficient and 10 economical drying of hat-forms particularly of the type built up of a plurality of strands of straw, fiber or the like which have preliminarily been woven, intertwined, twisted or compressed to establish simply a hat-brim and not a crown-and-brim structure. 15 This embodiment is designed, however, to be effectively used even for drying a structure of the kind last-mentioned, it should at this point be stated, as will appear clearly 20 hereinafter. The ultimate essence of the invention, then, may here at the very outset be indicated by reference to the presence of the frusto-conical wall 4, this making for the efficiency and economy aforesaid,—and 25 the coöperant presence of the wire-net roof, this last, in the light of the fact that said wall is preferably part of an integral, generally bowl-like heat-collecting member 3, making for the expedition, simplicity and 30 inexpensiveness aforesaid.

An object of the invention which may also be now specifically mentioned is the provision of an improved portable device of the above type.

Other objects and aims of the invention, more or less broad than those stated above, together with the advantages inherent, will be in part obvious and in part specifically referred to in the course of the following 40 description of the elements, combinations, arrangements of parts and applications of principles constituting the invention; and the scope of protection contemplated will appear from the claims.

In the accompanying drawing, which is to be taken as a part of this invention, and wherein is shown one of the various possible embodiments of the invention, as at present preferred:

Figure 1 is a top plan view of said embodiment; and Fig. 2 is a vertical sectional

view thereof, taken on the line A—A or on the line B—B of Fig. 1; the inverted deflector-cone and its preferably present sheathing of asbestos or the like being partially broken away in both figures the better to disclose a detail of construction of the wire-net roof.

Similar reference characters refer to similar parts throughout the several views of the drawing.

Referring now to the actual structure illustratively present, the reference numeral 3 represents as aforesaid, an integral, as a cast-iron, bowl-like member or heat-collecting vessel having an inverted frusto-conical side-wall 4 provided preferably with an upwardly centrally dished bottom wall 5 as shown to establish below the dish what may be termed a flame-chamber or cupola 6 70 adapted to have its under curved surface or ceiling 7 function endothermically when the flame-chamber is housing or placed in proper relation to a suitable heating source, as the flame 8 from a gas-jet 9.

It will be noticed in the present embodiment that the arched floor surface 10 (see Fig. 2), substantially paralleling ceiling 7, may be said to consist, in any axial section, of a pair of substantially similar lines each 85 of which is substantially at right angles with the adjacent line 11 that is defined by the cutting plane for said section. These lines first-mentioned would, in the case of the present embodiment, be spaced apart by 90 the presence of the upstanding socket 12.

The outer surface of wall 4 is preferably sheathed by a permanently attached sleeve 13 of some heat-deflecting material, as asbestos or the like, as shown.

The upper annular surface 14 of member 3 in the present instance is vertically drilled, for the forced-fit (see Fig. 2) accommodation of a plurality of pins 15, at equidistant points (Fig. 1). There are here eight of these drillings and pins, that pin additionally numbered 15' in Fig. 1 being broken away in that figure the better to indicate the manner in which each of the wire struts 16 is at its outer terminus coiled about the shank 100 of its pin 15. As best shown in Fig. 2, each of these struts is in the main L-shaped, the stem of the L lying horizontally, and said stem medially thereof having wound thereabout a coil 17 formed in a wire ring 18, the junction 19 between the said stem and the upstanding foot of the L being itself wound 105 110

about a smaller wire ring 20, and the free terminus of said foot being formed into a coil 21 that is wound about a wire ring 22 similar to wire ring 20. The structure thus 5 established will be hereinafter referred to as the centering means for a hat-brim.

The reference numeral 23 represents an inverted conical member, preferably drawn or spun of some thin sheet metal in the aid 10 of economy, and, having its outer surface preferably sheathed by a permanently attached sleeve 24 of some suitable heat-deflecting matter, as asbestos or the like, as shown, constituting a heat-deflector adapted 15 for convenient and instantaneous removal from the remainder of the embodiment. It is preferably maintained in place as illustrated, by the action of gravity, its inverted apex nesting with socket 12.

20 The operation of this embodiment of the invention should be largely obvious,—either with the member 23 associated therewith, in which event the embodiment is preferably employed to dry a hat-brim merely, or with 25 said member 23 removed, in which event the embodiment is preferably employed to dry a brim-and-crown hat.

But before pointing out some of the drying-efficiency characteristics of this embodiment, it should be noted that the preferably 30 cast-metal member 3, and the sleeve 13 of asbestos or the like, are not illustrated as drawn to correlative scales, for this is a matter of experiment and calculation with 35 which neither the invention nor this embodiment is concerned, it being sufficient here merely to state that the walls of member 3 are preferably of such uniform thickness throughout or of such varying characteristics 40 at different places as will best cause the same to absorb the maximum of heat delivered from flame 8 and then to radiate all or most of such absorbed heat into the interior of the member 3.

45 It is clear that the roof of the flame-chamber 6 will, especially if the jet 9 be so adjusted that the flame 8 spreads itself uniformly over the ceiling 7, absorb practically all of the heat generated from said flame; 50 this being due to the well-known law of thermal equilibrium. It is just as clear that all of this absorbed heat, due to the law last-mentioned and to the law of absorption and 55 radiation, will be delivered into the interior of member 3. And now the upwardly flaring wall 4 performs an important function in causing a uniform ascent of heated air into the uppermost zone of said interior of member 3; this wall 4 establishing a diffusing 60 stream-line or stream-slope for the rising heat-waves, the contemplated result being materially aided by the fact that the arched floor surface 10 here lies as described in the sixth preceding paragraph.

65 Let us say that it is desired to dry a straw

hat-brim, which ordinarily consists of a circular sheet of material having a central transverse opening. In such a case the conical member 23 is preferably in place as shown. The sheet of material is laid atop 70 the wire-net roof, the opening therein encompassing the centering means carried by said roof. Upon applying the flame 8, several things, additional to those mentioned in the immediately preceding paragraph, occur. 75 In the first place, none of the heat-waves delivered to the interior of member 3 is dissipated as loss through the opening in the hat-brim, for, due to the presence of the sleeve 24 on the conical member 23, none of 80 said heat-waves ever reach the latter to be absorbed thereby and then radiated for escape from the interior thereof. Next, the heat-waves that radiate from socket-adjacent portions of the arched floor surface 10 85 rise toward sleeve 24 to be reflected therefrom toward the hat-brim. Again, all heat that is absorbed by socket 12 must seek emergence therefrom away from flame 8, and this heat, deflected by sleeve 24, must 90 rise in the annular space located between the members 3 and 23.

Let us say, however, that it is desired to dry a straw brim-and-crown hat. The conical member 23 is in such a case preferably 95 removed from association with the rest of the embodiment. The hat is laid atop the wire-net roof, the crown encompassing and accommodating therein the centering means carried by said roof. The result is that 100 practically all the heat generated by flame 8 becomes transformed into ascending waves all of which must pass through the interstices of the hat and thoroughly and quickly 105 dry the same.

Inasmuch as many changes could be made in the above construction, and many apparently widely different embodiments of my invention could be made without departing from the scope thereof, it is intended that all 110 matter contained in the above description or shown in the accompanying drawing shall be interpreted as illustrative and not in a limiting sense.

It is also to be understood that the language used in the following claims is intended to cover all the generic and specific features of the invention herein described and all statements of the scope of the invention which, as a matter of language, might 120 be said to fall therebetween.

Having described this invention, what I claim as new, and desire to secure by Letters Patent, is:

1. In a device of the class described, a 125 heat collecting chamber having an opening in its top, said chamber having a side-wall that defines the frustum of an inverted cone, the floor wall of said chamber being upwardly centrally dished whereby the same 130

establishes therebelow a chamber into which may be directed an upwardly extending flame, in combination with a wire-net roof for said chamber adapted to be attached thereto to form a support for the article to be dried, said roof having formed therein a substantially central opening encompassed by an upstanding collar.

2. In a device of the class described, a heat collecting chamber having an opening in its top, said chamber having a side-wall that defines the frustum of an inverted cone, the floor-wall of said chamber being upwardly centrally dished, whereby the same establishes therebelow a chamber into which may be directed an upwardly extending flame, in combination with a wire-net roof for said chamber adapted to be attached thereto to form a support for the article to be dried, the outer surface of said side-wall being sleeved by asbestos or other suitable heat-resisting material.

3. In a device of the class described, a heat collecting chamber having an opening in its top, said chamber having a side-wall that defines the frustum of an inverted cone, in combination with a wire-net roof for said chamber adapted to be attached thereto to form a support for the article to be dried, and with an inverted conical heat-deflector centrally supported within said chamber and extending from the top to the bottom thereof.

4. In a device of the class described, a heat collecting chamber having an opening in its top, said chamber having a side-wall that defines the frustum of an inverted cone, in combination with a wire-net roof for said chamber adapted to be attached thereto to form a support for the article to be dried, and with an inverted conical heat-deflector centrally supported within said chamber and extending from the top to the bottom thereof, said member including a conical portion and a base-flange, the side-wall and apex of said portion being incased in a conical sheath of asbestos or other suitable heat-resisting material.

5. In a device of the class described, a heat collecting chamber having an opening in its top, said chamber having a side-wall that defines the frustum of an inverted cone, the floor-wall of said chamber being upwardly centrally dished whereby the same establishes therebelow a chamber into which may be directed an upwardly extending flame, in combination with a wire-net roof for said chamber adapted to be attached thereto to form a support for the article to be dried, and with an inverted conical heat-deflector centrally supported within said chamber and extending from the top to the bottom thereof, said deflector including a conical portion and a base-flange, the side-wall and apex of said portion being incased

in a conical sheath of asbestos or other suitable heat-resisting material.

6. In a device of the class described, a heat collecting chamber having an opening in its top, said chamber having a side-wall that defines the frustum of an inverted cone, in combination with a wire-net roof for said chamber adapted to be attached thereto to form a support for the article to be dried, and with an inverted conical heat-deflector centrally supported within said chamber and extending from the top to the bottom thereof, said deflector including a conical portion and a base-flange, the side-wall and apex of said portion being incased in a conical sheath of asbestos or other suitable heat-resisting material, the floor wall of said chamber carrying substantially centrally thereof a socket within which the apex of said sheath may be by gravity settled.

7. In a device of the class described, a heat collecting chamber having an opening in its top, said chamber having a side-wall that defines the frustum of an inverted cone, in combination with a wire-net roof for said chamber adapted to be attached thereto to form a support for the article to be dried, said roof having formed therein a substantially central opening encompassed by an upstanding collar, and with an inverted conical heat-deflector centrally supported within said chamber and extending from the top to the bottom thereof, said deflector including a conical portion and a base-flange, the side-wall and apex of said portion being incased in a conical sheath of asbestos or other suitable heat-resisting material, the floor wall of said chamber carrying substantially centrally thereof a socket within which the apex of said sheath may be by gravity settled, thereby to center said deflector when its base-flange rests upon said collar.

8. In a device of the class described, a heat collecting chamber having an opening in its top, said chamber having a side-wall that defines the frustum of an inverted cone, the floor-wall of said chamber being upwardly centrally dished whereby the same establishes therebelow a chamber into which may be directed an upwardly extending flame, in combination with a wire-net roof for said chamber adapted to be attached thereto to form a support for the article to be dried, and with an inverted conical heat-deflector centrally supported within said chamber and extending from the top to the bottom thereof.

9. In a device of the class described, a heat collecting chamber having an opening in its top, said chamber having a side-wall that defines the frustum of an inverted cone, the floor-wall of said chamber being upwardly centrally dished whereby the same

establishes therebelow a chamber into which may be directed an upwardly extending flame, in combination with a wire-net roof for said chamber adapted to be attached thereto to form a support for the article to be dried, and with an inverted conical heat-deflector centrally supported within said chamber and extending from the top to the bottom thereof, said deflector being sheathed

by a conical sleeve of asbestos or other suitable heat-resisting material.

Signed at New York in the county of New York and State of New York this 23 day of December A. D. 1914.

NAOMI FORCE.
